CAR DOOR

Wilfred A. Beauchamp, Chicago, Ill., assignor, by mesne assignments, to The Youngstown Steel Door Company, Cleveland, Ohio, a corporation of Ohio

Application November 15, 1933, Serial No. 698,059

14 Claims.

(Cl. 20—22)

This invention relates to car doors and concerns itself more particularly with that type of doors which is frictionally supported upon the car side in its normal or lowered position and elevated above its frictional support and disposed upon antifriction means when it is desired to move said doors toward open or closed position.

It is an object of this invention to provide lift mechanism in connection with a car door of substantial depth, comprising a metallic panel disposed in the main in substantially the outer plane of said door, and a horizontally extending backing plate secured to the lower portion of said panel and offset therefrom to lie substantially in the inner plane of said door whereby said mechanism may be placed between said panel and backing plate so as to decrease the projection thereof beyond the outer plane of the door.

A further object is to provide a car door with lift mechanism comprising an operating lever capable of assembly with said mechanism and attachment to said door while said door is mounted upon the car.

Other objects of the invention will become clear as the description thereof proceeds.

In the drawings forming part of this specification:

Figure 1 is a fragmentary elevation of a railway car showing the invention applied thereto;

Figure 2 is a fragmentary elevation of the lower left hand corner of the door shown on an enlarged scale;

Figure 3 is a horizontal section taken on line 3—3 of Figure 2;

Figure 4 is a sectional view taken on line 4—4 of Figure 1;

Figure 5 is a vertical section taken on line 5—5 of Figure 2;

Figure 6 is a vertical section taken on line 6—6 of Figure 2;

Figure 7 is a vertical section taken on line 7—7 of Figure 2; and

Figure 8 is a horizontal section taken on line 8—8 of Figure 1.

Referring to the drawings in which a preferred embodiment of the invention is illustrated, the numeral 10 designates a portion of the side of a railway house car upon which the door 11 is mounted for sliding movement. The door 11 is adapted to close a door opening 12, the front edge of which is defined by means of a Z-shaped door post 13, the inwardly disposed longitudinal flange 14 of which is secured to the car side, as indicated in Figure 3 of the drawings. The door post 13 is provided with a transversely extending web 15 and a longitudinally and rearwardly extending flange 16. The bottom of the door opening is defined by a side sill 17 constituting a part of the underframe of the car, said sill, as clearly appears from Figure 5 of the drawings being

formed by means of an angle, the vertically extending flange 18 of which projects upwardly a distance equal to the depth of the car floor 19 within the door opening. A threshold plate 20 overlies the outer portion of the floor and is provided with a return bend 21 within which the outwardly extending horizontal flange 22 of a reinforcing angle 23 is received. The angle 23 is secured to the side sill as by means of rivets 24. The side sill 17 is reinforced by means of a channel or similar member 25 which is secured to the horizontally extending flange 26 of a side sill, as shown in Figure 5 of the drawings. A plurality of track supporting brackets 27, one of which is shown in Figure 5 are secured preferably to the reinforcing channel member 25. These brackets 27 are adapted to support a track 28 disposed below the door opening. Said track comprises a horizontal flange 29 extending inwardly and secured to the brackets by means of rivets 30 and a downwardly extending flange 31.

The track 28 is adapted to support the door and mechanism of the instant invention. The door 11 comprises a metallic panel 32, vertical marginal reinforcing members 33 and 34, a bottom horizontally extending reinforcing member 35 and a top reinforcing member (not shown) of any desired construction. It is to be observed that the marginal reinforcing members such as 33, 34 and 35 define a door of substantial depth. As clearly shown in Figure 3 of the drawings the vertical reinforcing member 33 secured to the front margin of the door is comprised of a Z-shaped structural member, the flanges 36 and 37 of which extend, respectively, forwardly and rearwardly of the door. In the closed position of the door the flange 36 is adapted to enter behind the rearwardly extending flange 16 provided on the door post 13 so as to provide a weather seal at the front margin of the door. The marginal reinforcing member 34 secured to the rear of the door is formed of an angle member, the inwardly directed flange 38 of which is deformed as indicated at 39 so as to cooperate with a guard strip 40 secured to the car to exclude the weather. The bottom reinforcing member 35, which is of channel shape in section, is disposed with the flanges 41 and 42 thereof extending downwardly, the latter flange being secured to the panel 32 of the door by means of a plurality of rivets 43.

The panel 32, which may be of any desired construction, is substantially plane as shown in Figure 1 of the drawings and disposed substantially in the outer plane of the door defined by the rearwardly extending flange 37 of the front marginal reinforcing member 33. A backing plate 44 is secured to the inside of the panel 32 by means of a plurality of rivets 45. The backing plate 44 is offset as indicated at 46 so as to

provide a downwardly extending flange 47 disposed substantially in the inner plane of the door defined by the forwardly extending flange 36 of the reinforcing member 33. Adjacent its lower edge the flange 47 is secured to the flange 41 of the channel reinforcing member 35 by means of a plurality of rivets 48.

The door 11 in its normal or lowered position is adapted to be seated upon the supporting track 28 in frictional engagement therewith as clearly shown in the drawings. Lift mechanism is provided whereby said door may be elevated above the track and supported upon rolling means for movement upon the track. The lift mechanism is secured adjacent the lower corners of the door, as clearly shown in Figure 1 of the drawings, and is disposed for the most part within the space provided by the panel 32 and the backing plate 44. To permit this disposal of the lift devices the panel 32 of the door is cut away adjacent each lower corner thereof along the lines defined by the points designated by the reference characters *a*, *b*, *c*, and *d* and *a'*, *b'*, *c'* and *d'*, respectively. Within the cut away portion adjacent the front lower corner of the door the lift device 49 is secured. The lift device 49 comprises a reinforcing plate 50 secured as by means of rivets 51 to the backing plate 44. Adjacent the upper edge of the reinforcing plate 50 said plate is offset as indicated at 52 and 53, these offsets being provided with the longitudinally extending flanges 54 and 55 by means of which the reinforcing plate 50 is secured to the rearwardly extending flange 37 of the reinforcing member 33 and to the panel 32 of the door 11 by means of rivets 56. In order to drive these rivets the backing plate 44 is provided with openings 57 and 58. Said lift device comprises also a cover plate 59 secured to the panel 32 in part by means of the rivets 45 which secure the backing plate 44 to said panel and by the rivets 56 which secure the reinforcing plate 50 to the rearwardly extending flange 37 and to the panel 32. The cover plate 59 is disposed so as to cover the cut away portion of the panel. A roller retaining member 60 provided with aligned oppositely extending trunnions 61 and 62 is journaled in bearings 63 and 64 provided, respectively, in the reinforcing plate 50 and in the cover member 59. The roller retaining member carries a roller 65 mounted upon a pin or axle 66 by means of a roller bearing 67. The pin 66 for the roller 65 is offset longitudinally with respect to the trunnions 61 and 62 provided on the roller retaining member 60. The mounting of the roller retainer and its roller is such that the roller preferably is in engagement with the door supporting track 28. The cover plate 59, in addition to the securement to the door set forth above, is also secured adjacent the lower edge thereof to the backing plate 44. To this end the flange 37 of the marginal reinforcing member 33 stops short of the lower edge of the door as indicated at 68 and the cover plate 59 is offset inwardly as indicated at 69 and then extended downwardly to provide a flange 70 by means of which the cover member is secured to the vertical flange 47 of the backing plate by means of the rivet 71.

The trunnion 62 provided on the roller retaining member 60 is extended outwardly beyond the bearing 64 formed in the cover plate 59. Said trunnion 62, which is normally substantially cylindrical, is provided with the parallel faces 72 and 73. The trunnion 62 thus formed is adapted to have operative engagement with an oper-

ating lever 74 which is provided with a slot 75 in its lower portion, said slot, as clearly indicated in Figure 2 of the drawings, opening through the lower edge of the operating lever. Disengagement of the lower portion of the operating lever 74 from the trunnion 62 by movement transversely to the door is prevented by means of the flanges 76 and 77 formed on the cover plate. These flanges are adapted to overlap corresponding flanges 78 and 79 formed on the lower portion of the operating lever. It will be apparent, however, from Figure 2 of the drawings that the flanges 76 and 77 of the cover plate do not prevent engagement of the operating lever with the trunnions 62 by a substantially sliding movement of the operating lever. The cover plate additionally is provided with a substantially hook shaped portion 80 which is adapted to be interlocked with the flange 31 of the track 28 in order to prevent disengagement of the lower portion of the door from the track.

A lift device 81, substantially similar to the lift device 49 is secured to the door adjacent the lower right hand corner thereof. The lift device 81 comprises a reinforcing plate 82, a cover plate 83 associated with the backing plate and panel as heretofore described and to which a roller retaining member 84, carrying a roller 85, is journaled. It is to be observed that the cover plate 83 is not provided with flanges similar to the flanges 76 and 77 provided on the cover plate 59, but that the trunnion 86 of the retaining member 84 is extended outwardly beyond the cover plate so that in the event of destruction or breakage of the trunnion 62 and operating lever 74 the trunnion 86 may be engaged as by means of a wrench in order to operate the lift devices. The cover plate 83 is provided with a hook shaped portion 88' adapted to engage the depending flange 31 of the track in order to prevent disengagement of the lower portion of the door from the track.

To obtain simultaneous operation of the lift devices the roller retaining members 60 and 84 are connected together. For this purpose the roller retainer 60 is provided with an angular lug 87 and the roller retainer 84 is provided with a corresponding lug 88. These lugs are adapted to extend through openings 89 and 90 formed in a connecting bar 91 disposed within the space provided by the panel and the offset backing plate. It will be apparent from the foregoing that actuation of the operating lever 74 will impart simultaneous movement to the roller retaining members 60 and 84 in order to elevate 55 the door about the rollers as trunnions.

Means is provided whereby disengagement of the operating lever 74 from the trunnion 62 is prevented, said means serving, moreover, to permit replacement of the operating lever 74 in the event said lever is broken or lost without the necessity of removing the door from the car for such replacement. Accordingly, a keeper member 92 is provided and is preferably arcuate in form. The keeper member 92 is secured as by means of rivets 93 to the door. The operating lever 74 is formed with an inwardly extending lug 94 lying below the keeper member 92 and with a downwardly extending finger 95 offset inwardly from the lever 74 as indicated at 96 so as to provide space between the finger 95 and the lever to receive a flange 97 formed on the keeper 92. In view of this structure it will be evident that the operating lever 74 cannot be raised sufficiently because of the engagement between the 75

keeper 92 and the lug 94 provided on the lever to bring about disengagement of the lower portion of the lever from the trunnion 62. It will also be evident that by means of the interlocking flanges provided on the lower portion of the lever and on the cover plate 59 that the lever cannot be disengaged from the trunnion 62 by an outward movement of the lever. However, if it becomes necessary to replace the lever such replacement may be had by merely removing the rivets 93 which secure the keeper 92 to the door engaging the lower portion of the lever with the trunnion 62 by a substantially sliding movement of the lever and again riveting the keeper 92 to the door so as to establish the relationship between said keeper and the lug 94 and finger 95 provided on the operating lever as hereinabove described. In this mode of replacement of the lever it is obvious that the door may remain upon the car.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a railway car door comprising a metallic panel disposed in substantially the outer plane of said door, a horizontally extending backing plate secured to the lower portion of said panel, said backing plate being offset inwardly from said panel and disposed in substantially the inner plane of said door, said panel being coped adjacent the lower corners of said door, elevating mechanism insertable through each of said coped portions having operative relationship with said door and a cover plate for closing each of said portions secured to said door.

2. In a railway car door comprising a metallic panel disposed in substantially the outer plane of said door, a horizontally extending backing plate secured to the lower portion of said panel, said backing plate being offset inwardly from said panel and disposed in substantially the inner plane of said door, said panel being coped adjacent the lower corners of said door, elevating mechanism insertable through each of said coped portions, said mechanism comprising a roller and a roller retainer provided with a trunnion rotatably mounted upon said backing plate, a plate secured to said door for covering each of said coped portions, a bearing formed in each of said cover plates and a second trunnion on each of said retainers aligned with said first mentioned trunnion journaled in said cover plate, an operating lever secured to one of said second mentioned trunnions and a bar disposed between said panel and backing plate connecting said roller retainers for simultaneous movement.

3. In a railway car door comprising a metallic panel disposed in substantially the outer plane of said door and vertical marginal reinforcing members having flanges secured to said panel, a horizontally extending backing plate secured to the lower portion of said panel, said backing plate being offset inwardly from said panel and disposed in substantially the inner plane of said door, said panel being coped adjacent the lower corners of said door, a reinforcing plate secured to said backing plate in opposed relationship with each of said coped portions, outwardly offset longitudinally extending flanges provided on each of said reinforcing plates, a cover plate having

longitudinally directed flanges covering each of said coped portions, certain of said flanges of said reinforcing and cover plates being secured to said panel, the remaining flanges thereof being secured to said flanges of the vertical marginal reinforcing members and elevating mechanism disposed between and journaled in said reinforcing and cover plates.

4. In a railway car door comprising a metallic panel disposed in substantially the outer plane of said door and vertical marginal reinforcing members having flanges secured to said panel, a horizontally extending backing plate secured to the lower portion of said panel, said backing plate being offset inwardly from said panel and disposed in substantially the inner plane of said door, said panel being coped adjacent the lower corners of said door, a reinforcing plate secured to said backing plate in opposed relationship with each of said coped portions, outwardly offset longitudinally extending flanges provided on each of said reinforcing plates, a cover plate having longitudinally directed flanges covering each of said coped portions, certain of said flanges of said reinforcing and cover plates being riveted to said panel which is disposed between said flanges, the remaining flanges being riveted to said flanges of the vertical reinforcing members, said backing plate being provided with apertures, whereby said rivets may be driven to secure said parts together and elevating mechanism disposed between and journaled in said reinforcing and cover plates.

5. In a railway car door comprising a metallic panel disposed in substantially the outer plane of said door and vertical marginal reinforcing members having flanges secured to said panel, a horizontally extending backing plate secured to the lower portion of said panel, said backing plate being offset inwardly from said panel and disposed in substantially the inner plane of said door, said panel being coped adjacent the lower corners of said door, a reinforcing plate secured to said backing plate in opposed relationship with each of said coped portions, outwardly offset longitudinally extending flanges provided on each of said reinforcing plates, a cover plate having longitudinally directed flanges covering each of said coped portions, certain of said flanges of said reinforcing and cover plates being riveted to said panel which is disposed between said flanges, the remaining flanges being riveted to flanges directed toward each other and provided on vertical reinforcing members secured to the vertical margins of said door, said latter flanges lying substantially in the outer plane of said door, said backing plate being provided with apertures whereby said rivets may be driven to secure said parts together, the flanges of said cover plates secured to said vertical reinforcing members being offset inwardly adjacent the lower portions thereof whereby said flanges may be secured to said backing plate, the flanges of the vertical reinforcing members stopping short of the lower edge of said door to permit offsetting of said cover plate flanges and elevating mechanism disposed between and journaled in said reinforcing and cover plates.

6. In a railway house car, a door adapted to be frictionally supported upon said car, elevating mechanism including rolling means for lifting and supporting said door for antifrictional longitudinal movement relative to said car, an operating lever for said mechanism slidably engaged therewith by movement in a plane substantially

- parallel to said door, said door and the lower portion of said lever being provided with flanges interlockingly engaged by said sliding movement of the lever to prevent disengagement of said portion of said lever from said mechanism by an outward movement thereof and a member secured to said door and associated with said lever for retaining said lever upon said door whereby said lever may be disengaged from or associated with said elevating mechanism by a substantially sliding movement in a plane parallel to said door upon removal of said member while said door is mounted upon said car.
7. In a railway house car, a door adapted to be frictionally supported upon said car, elevating mechanism including rolling means for lifting and supporting said door for antifrictional longitudinal movement relative to said car, an operating lever for said mechanism adapted to be engaged therewith and disengaged therefrom by a substantially sliding movement in a plane parallel to said door while said door is mounted upon said car and a member adapted to be secured to said door and associated with said lever to prevent opposite sliding movement of said lever and disengagement thereof from said mechanism.
8. In a railway house car, a door adapted to be frictionally supported upon said car, elevating mechanism including rolling means for elevating and supporting said door for antifrictional longitudinal movement relative to said car, an operating lever for said mechanism adapted to be engaged therewith and disengaged therefrom by a substantially sliding movement while said door is mounted upon said car, a member adapted to be secured to said door and associated with said lever to prevent opposite sliding movement of said lever and disengagement thereof from said mechanism, and means upon said car having interlocking engagement with said lever to prevent disengagement thereof from said mechanism by an outward movement of said lever.
9. In a railway house car, a door adapted to be frictionally supported upon said car, elevating mechanism including rolling means for lifting and supporting said door for antifrictional longitudinal movement relative to said car, an operating lever for said mechanism adapted to be engaged therewith and disengaged therefrom by a substantially sliding movement while said door is mounted upon said car, a member adapted to be secured to said door and associated with said lever to prevent opposite sliding movement of said lever and disengagement thereof from said mechanism, and means upon said car having interlocking engagement with said lever and means upon said lever having interlocking engagement with said member to prevent disengagement thereof from said mechanism by an outward movement of said lever.
10. In a railway house car, a door adapted to be frictionally supported upon said car, elevating mechanism comprising a roller retainer provided with oppositely extending trunnions and a roller journaled in said door adjacent each of the lower corners thereof, one of the trunnions of a roller retainer extending outwardly beyond said door, an operating lever for said mechanism provided with a slot opening through the edge of said lever adapted to operatively receive said one trunnion by a substantially sliding movement of said lever, means engaging the lower portion of said lever for preventing outward movement of said portion relative to said trunnion and a member secured to said door adapted to engage and prevent opposite sliding movement of said lever and disengagement thereof from said member.
11. In a railway house car, a door adapted to be frictionally supported upon said car, elevating mechanism comprising a roller retainer provided with oppositely extending trunnions and a roller journaled in said door adjacent each of the lower corners thereof, one of the trunnions of a roller retainer extending outwardly beyond said door, an operating lever for said mechanism provided with an opening in the lower portion thereof adapted to operatively receive said one trunnion and means secured to said door adapted to engage said lever to prevent disengagement thereof from said trunnion.
12. In a railway house car, a door adapted to be frictionally supported upon said car, elevating mechanism comprising a roller retainer provided with oppositely extending trunnions and a roller journaled in said door adjacent each of the lower corners thereof, one of the trunnions of a roller retainer extending outwardly beyond said door, an operating lever for said mechanism provided with a slot opening through the lower edge of said lever adapted to operatively receive said one trunnion by a substantially sliding movement of said lever, means engaging the lower portion of said lever for preventing outward movement of said portion relative to said trunnion and a member secured to said door adapted to engage and prevent opposite sliding movement of said lever and disengagement thereof from said trunnion.
13. In a railway house car, a door adapted to be frictionally supported upon said car, elevating mechanism comprising a roller retainer provided with oppositely extending trunnions and a roller journaled in said door adjacent each of the lower corners thereof, one of the trunnions of a roller retainer extending outwardly beyond said door, an operating lever for said mechanism provided with a slot opening through the lower edge of said lever adapted to operatively receive said one trunnion by a substantially sliding movement of said lever and a member secured to said door adapted to overlie a projection provided on said lever to prevent opposite sliding movement of said lever and disengagement thereof from said trunnion.
14. In a railway house car, a door adapted to be frictionally supported upon said car, elevating mechanism comprising a roller retainer provided with oppositely extending trunnions and a roller journaled in said door adjacent each of the lower corners thereof, one of the trunnions of a roller retainer extending outwardly beyond said door, an operating lever for said mechanism provided with a slot opening through the lower edge of said lever adapted to operatively receive said one trunnion by a substantially sliding movement of said lever, means engaging the lower portion of said lever for preventing outward movement of said portion relative to said trunnion and a member secured to said door adapted to overlie a projection and be interlocked with a flange provided on said lever to prevent opposite sliding movement of said lever and disengagement thereof from said member.

WILFRED A. BEAUCHAMP.
